GUMMING MACHINE

Kurt Kaufmann, Berlin-Waidmannslust,
Germany, assignor to Fritz KrochApplication December 31, 1938, Serial No. 248,711
In Germany September 9, 1938

4 Claims. (Cl. 91—49)

This invention relates to apparatus for applying gum to a web of paper, which latter, if desired, may also comprise a series of overlapping blanks.

5 **Apparatus, more particularly for the application of dry gum, having a gumming roller, past which there is moved the web of paper to be gummed, which may consist of separate blanks arranged to overlap one another in fish-scale fashion, are old in themselves.**

In the known gumming apparatus of this character the provision of a thin and even layer of the adhesive on the gumming roller, and accordingly the application of strips of gum of uniform 15 thickness to the web of paper being treated, is confronted by difficulties due primarily to the fact that it is impossible to provide a suitable scraper for the adhesive at the correct point.

It is the object of the invention to overcome 20 this drawback, and in the accomplishment of this object the invention accordingly consists of an apparatus for applying gum to a web of paper, or a series of separate overlapping blanks, which comprises a gumming roller, means for moving 25 the web of paper or the overlapping blanks past the gumming roller, and a stationary hollow cylinder filled with gum and arranged adjacent the application or coating roller, the said hollow cylinder having at least one outlet slot opening out 30 into a sickle-shaped recess in the outer face of the cylinder and being made to bear with this recess in such a manner against the gumming roller that the peripheral face of the gumming roller moves past the said outlet slot in close 35 proximity thereto and is thus supplied with gum from the hollow cylinder.

In accordance with an additional feature of the invention the hollow cylinder is so disposed in relation to the gumming roller that the latter, 40 moving past the outlet slot in the hollow cylinder in the direction from the top towards the bottom, is situated to a slight extent away from the cylinder at the upper edge of the sickle-shaped recess, whilst it bears closely against the cylinder below 45 the outlet slot, so that between the hollow cylinder and the gumming roller there is formed a nozzle-like gap tapering in the direction towards the slot.

In its movement past the outlet slot in the hollow cylinder the gumming roller, in a manner of speaking, sucks up the gum out of the cylinder in the form of a thin layer, and upon its rotation it continuously forces the excess of gum back into the cylinder through the nozzle-like gap between 55 the cylinder and the gumming roller, in consequence of which the gumming roller is continuously surrounded with a film of adhesive of even thickness. At the same time any foreign matter which may be present in the layer of adhesive 60 after leaving the web of paper is scraped off by

the upper edge of the sickle-shaped recess in the hollow cylinder and is retained on the outer face of the cylinder above the recess. The sickle-shaped recess in the outer face of the hollow cylinder, against which the gumming roller is caused to move, also acts in the manner of a distributing surface, by means of which the adhesive passing out of the outlet slot is subjected to a refining action.

5 An apparatus according to the invention has 10 the advantage that it permits of any desired position of the web of paper under treatment in relation to the gumming roller, including a horizontal disposal of the web below the gumming roller, this position having the advantage that the application of the gum to the paper can be observed particularly well.

The apparatus as set forth also has the advantage that the adhesive accommodated within the hollow cylinder is protected almost completely 20 against the access of air, so that it is unable to coagulate, at least to any appreciable extent.

The invention is illustrated by way of example in the accompanying drawings, in which

Fig. 1 is an elevational view, partially in section, of one embodiment of the apparatus according to the invention.

Fig. 2 shows a portion of Fig. 1 on enlarged scale.

Fig. 3 is a plan view in the direction of the arrow III in Fig. 1.

Fig. 4 shows a section of a web of paper, made up of separate overlapping blanks, which is to be furnished with two strips of adhesive by means of the apparatus according to Fig. 1.

35 Fig. 5 is an elevational view, partially in section, of a modified form of apparatus.

In the embodiment illustrated in Fig. 1 there is rotatably mounted between the two side walls 1, 1 of a frame the gumming roller 3, which during 40 the coating operation is driven continuously in the direction of the arrow 2. A web of paper is moved in any suitable fashion past the roller 3 in the direction of the arrow 4, for example by means of conveying belts. In the particular example shown this web 5 is made up of separate overlapping envelope blanks 6.

In its movement past the gumming roller 3 the web 5 is preferably pressed against the roller by a presser roller 7. To the side of the gumming 50 roller 3 there is provided a hollow cylinder 8, which is stationary during the coating operation and can be filled with adhesive through an upper opening 9, in which connection, for the purpose of effecting continuous refilling, there can 55 be provided on the hollow cylinder 8 a filling vessel 10. The two ends 11, 11 engaging in stopper-like fashion in the cylindrical body 8 are mounted on the studs 12, 13 of bolts 14, 15. The latter are rotatably mounted in clamping jaws 18, 60

which are shiftable along slideways or guide faces of the side walls 1, 1, so that by means of bolts 19, 19 engaging with the members 18 the hollow cylinder can be pressed to greater or 5 smaller extent against the roller 3.

By means of the clamping screws 20 the bolts 14, 15, and accordingly the hollow cylinder 8, can be adjusted transversely and clamped down in 10 position. Threaded bolts 21 engaging in longitudinal slots in the members 18, 18 serve to secure the hollow cylinder 8 in relation to the roller 3. The threaded bolt 15 is pressed continuously against the hollow cylinder 8 by means of a spring 16. For the purpose of replacing the hollow cylinder 8 it is merely necessary to withdraw the bolt 15 by means of the knob 17, whereby the stud 13 is disengaged from the end portion 11 and the cylinder 8 can be removed from the apparatus.

20 For the purpose of fine adjustment of the angular position of the hollow cylinder 8 there is provided on the latter a lever or arm 22, which engages at its lower end between a roll 23 and an adjustment screw 24, which is passed through 25 a bar 25 extending between the side walls 1, 1. The roll 23 is rotatably mounted on a lever 29 which in turn is pivotally supported at 26 by an angle member 27, which is secured to the bar 25. A spring 28 presses the roll 23 continuously 30 against the arm 22, and accordingly the arm 22 against the adjustment screw 24. The supporting lever 29 for the roll 23 possesses a handle 30 extending beyond the axis 26, by means of which 35 handle the roller 23 can be rocked temporarily away from the arm 22 when the cylinder 8 is being fitted in position.

An essential feature resides in the provision in the peripheral face of the cylinder 8 of a sickle-shaped recess 35, which is adapted to the periphery of the gumming roller 3 and into which there opens out the outlet slot 32 for conveying gum out of the cylinder 8. The angular position of the cylinder 8 is so adjusted by the means described that this cylinder assumes in relation to 45 the gumming roller 3 approximately the position shown in Fig. 2, in which at the upper edge 31 of the recess 35 the gumming roller 3 is situated a slight distance away from the cylinder 8, whilst below the outlet slot 32 it bears closely against 50 the hollow cylinder. There is accordingly formed between the hollow cylinder 8 and the gumming roller 3 a nozzle-like gap of greater or smaller width at the upper end dependent on the angular position of the cylinder 8.

55 If the gumming roller 3 rotates in the direction of the arrow 2, it sucks up adhesive in a thin layer out of the slot 32 in the direction of the arrow 33 and then transfers the same to the web 5 when passing the latter. Any adhesive not applied by the roller to the paper reaches upon the 60 additional rotation of the roller 3 in the nozzle-like gap between the roller and the hollow cylinder and is forced back by the roller 3 into the cylinder 8 through the slot 32. Any particles of 65 foreign matter adhering to the roller 3 after contact with the paper are scraped off by the edge 31 and are deposited on the outside of the cylinder 8 above the edge 31. The roller 3 in contacting with the paper accordingly possesses continuously a thin layer of adhesive of uniform 70 thickness and not contaminated with impurities of any kind.

The embodiment illustrated in Fig. 5 differs from that described merely by the fact that the web of paper 5 is moved against the roller 3 in a horizontal direction, i. e., in the direction of the arrow 34, which has the advantage that the 5 application of the adhesive is open to visual control.

In this case, therefore, the adjustment arm 22 must be provided, not at the centre, but at one of the two ends. The remaining embodiment 10 and also the operation of the apparatus according to Fig. 5 are the same as in the first embodiment described.

What I claim as new and desire to secure by Letters Patent is:

1. In apparatus for applying gum to a web of paper or to a series of separate overlapping blanks, the combination of a cylindrical gumming roller, means for moving an article to be coated past said roller, a stationary gum receptacle provided with a crescent shaped elongated recess at its outer face adjacent to the periphery of said roller, a conduit for conducting gum from the interior of said receptacle to said recess, said recess and said roller being adjustable relative 20 to each other to provide a variable distance therebetween to thereby regulate the amount of gum which adheres to the surface of said roller as it passes out of said recess.

2. In an apparatus for applying gum to a web 30 of paper or a series of separate overlapping blanks, a gumming roller, means for moving the web of paper or the overlapping blanks past the gumming roller, a stationary hollow cylinder arranged adjacent the said gumming roller and having a peripheral sickle-shaped recess adapted to co-operate with the said gumming roller for applying a thin layer of gum to the said gumming roller, the said hollow cylinder having at least one outlet slot opening out into the sickle-shaped recess for the purpose of transferring gum from the interior of the said hollow cylinder to the said recess and thence to the said gumming roller, and means for adjusting the desired angular position of the said hollow cylinder 45 in relation to the said gumming roller.

3. An apparatus as claimed in claim 2, in which the said means for adjusting the angular position of the hollow cylinder comprise an adjustment screw and a resilient counter-stop and at least one arm secured to the hollow cylinder and engaging at its opposite end between the said adjustment screw and the said counter-stop, the said adjustment screw permitting of fine adjustment of the said arm.

4. In apparatus for applying gum to a web of paper or to a series of overlapping blanks, the combination of a stationary gum receptacle provided with a crescent shaped longitudinal recess at its outer face, a conduit for conducting gum 60 from the interior of said receptacle to said recess, a cylindrical gumming roller positioned to extend into said recess to provide a space between the wall of said recess and said roller whose width perpendicular to the periphery of said roller decreases in the direction of rotation of the latter, adjustable mounting means for said receptacle affording adjustment of the latter relative to said roller for regulating the width of said space to thereby vary the amount of gum 65 adhering to the surface of said roller as it leaves said recess.

KURT KAUFMANN.
